UNITED STATES PATENT OFFICE.

JOHN P. HULTGREN, OF CHICAGO, ILLINOIS.

CENTRIFUGAL CREAM-SEPARATOR.

1,101,799.

Specification of Letters Patent. Patented June 30, 1914.

Application filed May 24, 1913. Serial No. 769,626.

To all whom it may concern:

Be it known that I, JOHN P. HULTGREN, residing at Chicago, in the county of Cook and State of Illinois, have invented certain new and useful Improvements in Centrifugal Cream-Separators, of which the following is a description, reference being had to the accompanying drawings, forming a part of this specification, in which corresponding numerals of reference in the different figures indicate like parts.

The object of my invention is to provide a centrifugal cream separator which shall be simple and cheap in construction, easily manipulated and, withal, durable and highly efficient.

To these ends, my invention consists in novel means for feeding the whole-milk to the bowl and into contact with the interior 20 of a separating member so as to cause a considerable initial separation of the different gravities during the act of delivery to, and before a general distribution thereof is made upon the surface of said separating member.

Other novel and important features of 25 said invention consist in the form and construction of the separating member or members, whereby, with a minimum number of parts, a maximum distribution for skimming 30 purposes may be made of the inflowing milk upon its delivery to the interior of the separating member, after which the centrifugal action may cause the liquid of different gravities to flow upon different areas, 35 thereby dividing them into distinct currents leading toward separate outlets; all of which is hereinafter more particularly described and definitely pointed out in the claims.

In the drawings, Figure 1, is an axial, vertical sectional view of a separating bowl embodying the features of my invention, 40 said section being in the plane of the milk delivery or feed-wings. Fig. 2 is a like view 45 taken in a plane at right angles to that shown in Fig. 1. Fig. 3 is a sectional view in plan taken upon the line 3, Fig. 2. Fig. 4, is a plan view in detail of the inner separating member. Fig. 5, is a view of the 50 combined base and feed-member. Fig. 6, is a sectional view in plan taken upon the line 6, Fig. 1. Fig. 7, is a central vertical section of a bowl showing a modified construc-

tion, and Fig. 8, is an elevation of a modified separating member like that shown in 55 the other views except that the outlet openings are differently located.

Referring to the drawings, 1, Figs. 1, 2, 3 and 5, represents generally the bottom of the bowl, a portion 2, of which is of hollow 60 conoidal shape, as more clearly shown in Figs. 2 and 5. Said part 2, is concentric with the axis of the bowl and integral with an axial feed-tube 3, which is extended upwardly therefrom. A central vertical bore 4, 65 is formed in said member for the reception of a driving spindle, not shown, which may be operatively connected therewith in any well known way. The conduit portion of the feed-tube is preferably extended downwardly to about midway between the top and bottom of the bowl and is restricted at the top by means of the usual annular flange 5. Wings 6, 6, are formed upon and extended radially from the feed-tube to the wall 70 of the separating member and downwardly to the bottom of the bowl. Said wings are provided with downwardly inclined conduits 7, 7, from the outer ends of which extension conduits or grooves 8, 8, are led 75 downwardly substantially to the level of the bottom of the bowl, from whence they are curved outwardly as shown at 9, Figs. 1 and 5. Lateral flanges 10, 10, Figs. 3, 5, and 6, are formed upon each of the wings, the 80 special construction and function of which will be explained later.

Located within the bowl, so as to surround the feed-tube, is a separating member generally designated by 11, which is formed 90 from sheet-metal and consists of an inverted cup-shaped structure, the peculiar form of which constitutes one of the novel features of the invention and is of especial importance, inasmuch as it aids materially in separating the lighter from the heavier gravities 95 of the liquid and in distributing them in separate currents leading to separate outlets. Said member is circular at the base and, preferably, for a short distance upwardly 100 therefrom, and is provided with a horizontal flange 12, at the bottom, which is adapted to fit against a circular upturned bead 13, by which it is axially centered and securely held in place. A ring 14, is formed 105 upon the top of said member so as to fit ac-

curately around the feed-tube; a notch 15, Fig. 4, being formed therein for the reception of a spline 16, Figs. 2 and 5, which insures its proper adjustment. Formed in the 5 ring 14, are cream openings 17. The upper portion 18, of said separating member corresponds in the degree of inclination to, and is adapted to fit and rest upon the wings 6, as shown in Fig. 1. While, as stated, the 10 base or bottom portion of the separating member 11, is circular in cross-section, the upper part is elliptical; the change of form commencing at a level near the base, as better shown in Fig. 8, from whence it gradually 15 assumes a complete oval. The wings, if there are but two, as I prefer, are intended to be located in the vertical plane of the long axis of the oval, as shown in Figs. 1 and 3, and the peripheral surfaces of the upper 20 and lower portions of said wings, as shown at 19 and 20, respectively, are formed to fit closely against the inner periphery of the separating member 11. Said wings, or rather the flanges 10, thereon, are cut away 25 as shown at 21, Figs. 1, 5 and 6, to form narrow spaces between said flanges and the inner wall of the separating member for the purpose of causing the full-milk, when delivered, to pass in thin films or laminæ 30 therethrough. The separating member 11, is provided with openings 22, Figs. 2, 3 and 4, arranged preferably in a horizontal row at or near the top of the main portion thereof and upon the short axis of the ellipse, for 35 the passage of the partially separated milk to the outer periphery of said member.

Surrounding and inclosing the separating member 11, is a second separating member 23, which is spaced therefrom and is, in 40 form and construction, identical therewith except as to size and the location of the outlet openings for the milk, said openings, designated by 24, Figs. 1 and 2, being formed in a horizontal row around the entire base 45 of said member for the purpose hereinafter stated. The bottom of the member 23, rests upon the circular flange 12, of the member 11, and against the annular flange 13. Cream openings 25, Fig. 2, are formed in a 50 ring at the top of said member corresponding to the ring 14, which is notched in like manner to receive the spline 16. This adjustment serves to insure the registration of the cream openings 25, with the cream 55 openings 17, in the member 11.

A circular conical hood or cover 26, is adapted to rest upon ribs or blocks 23^a, upon the top of the member 23, the latter being in the plane of the long axis of said member. 60 Said hood is provided with the usual neck portion 27, of larger diameter than that of the feed-tube, so as to leave an annular space between them and provide for an in-turned annular flange 28, at the top which 65 is fitted upon the feed-tube and serves to

center said hood. The usual cream-outlet screw 28^a, is formed in said neck so as to communicate with the annular cream-space upon its inner periphery.

A bowl 29, of well known form, is arranged to inclose the parts described, the bottom portion thereof being fitted within a flange 30, upon the bottom member 1. The upper or conical part of the bowl is made to conform in shape to the hood 26, and is spaced therefrom in a well known way by means of ribs upon the latter. The usual skim-milk outlets 32, Fig. 1, are formed in the neck 33, of the bowl at a level below that of the cream outlet. The several parts described are rigidly secured in place by means of a nut 34, threaded upon the upper end of the feed-tube and arranged to bear against the top of the neck 33, and the flange 28, of the hood.

Having thus fully described the apparatus, I will now explain its operation: The whole-milk, upon being admitted to the feed-tube, is diverted radially through the channels 7, the ends of which are in close proximity to the walls of the separating member 11, as clearly shown in Figs. 1 and 3. The streams are deflected downwardly by said walls into the grooves 8, which are kept full and under constant pressure from 95 top to bottom, thereby causing the full-milk to be discharged evenly and in thin films through the narrow lateral passage-ways between the inner wall of the separating member 11, and the cut-away portions 21, 100 of the flanges 10, formed upon the wings 6. The milk, which is necessarily under great stress at all times after entering the feed-tube, is thus caused to be delivered into the interior of the lower or circular zone of the 105 separating member 11, against the inner periphery, upon the surface of which it is thoroughly distributed so as to produce an active skimming effect. The passage there-to through the narrow channels or spaces 110 between said separating member and the flanges 10, causes a stress upon the associated particles or globules, resulting in an initial separation of the different gravities, and as the body of milk and partially separated 115 cream is delivered into the interior of the separating member 11, it is in a measure transformed and in condition to insure a rapid separation as soon as it is admitted thereto. After being first distributed around 120 the entire periphery of the base or lower portion of said member, it is then caused to rise; and as it is brought into contact with the beginning of the oval portion, the heavier gravities tend toward the longer and 125 the lighter ones toward the shorter axis of said member. The cream being next to the feed-tube, is discharged upwardly through the cream outlets 17, while the milk, with a 130 percentage of unseparated cream, is dis-

charged through the apertures 22, and conveyed downwardly between the members 11, and 23, to the base where the heavier gravities are discharged through the openings 24, to the inner periphery of the bowl. In its downward passage a further separation or skimming occurs, the cream so separated, passing upwardly to be discharged through the openings 25. After its passage through the openings 24, the skim-milk is caused to pass upwardly upon the inner periphery of the bowl in a well known way and into the space between the conical part of said bowl and the cover 26, to the skim-milk outlets 32. Such further percentage of cream as may be skimmed from the milk after passing the openings 24, is caused to pass upwardly upon the outside of the member 23, and beneath the hood 26, to mingle with the cream passing through the openings 17 and 25, to be finally discharged through the cream-opening 28.

While I prefer to employ two or more separating members, I have found in practice that good results may be accomplished with one. In the use of one, however, I would recommend a different disposition of the outlet openings. In Figs. 7 and 8, I have shown such a modification; and, inasmuch as the location of the outlet openings constitutes the only change, the reference numerals to the other parts have been retained. Outlet openings 35, are formed in the body of said separating member extending in a vertical plane in the short axis of the oval, from the bottom nearly to the inclined portion 18.

In the example illustrated, I have shown what, in view of all conditions, I regard as the best form or contour for the separating member; the aim being to so construct the lower portion thereof as to provide a horizontal circular zone therein concentric with the axis, for causing a uniform and maximum liquid distribution at the inception of the process, and combining therewith another and higher zone having separating areas at varying distances from said axis so that the varying gravities of the liquid, according as they are heavy or light, may tend toward one or the other of said areas. It follows, therefore, that while the lower zone should be circular, the upper one need not be elliptical in cross-section, provided that its contour is such as to furnish separating areas at varying distances from the axis; hence, while I prefer the elliptical form, I do not wish to be limited thereto, nor do I intend to limit myself to the relative positions shown of the wings, nor to the number of such wings nor to the number or relative area of the flanges formed thereon, inasmuch as all of these features may be varied without departing from the spirit of the invention.

Having thus described my invention, I claim:

1. A separating member for use in a centrifugal cream separator, consisting of a hollow structure having its lower portion circular and its upper portion elliptical in cross-section, in combination with an axial feed-member provided with wings having discharge openings arranged in the plane of the long axis of the elliptical part of said separating member and in close proximity to the inner wall of said separating member. 70

2. A separating member for use in a centrifugal cream separator, consisting of a hollow structure having its lower portion circular and its upper portion elliptical in cross-section, in combination with an axial feed-conduit provided with radial wings having discharge openings in the plane of the long axis of the elliptical part of said separating member and in close proximity to the inner wall thereof and means for discharging the milk in a thin film against said wall while directing it under stress in substantial parallelism therewith. 80

3. A centrifugal cream separator comprising a bowl having an axial whole-milk inlet, cream and skim-milk outlets, a hollow separating member having horizontal zones at different levels, the lowermost being concentric with the axis while that above is provided with separating areas at varying distances from said axis, and means connected with said axial inlet for directing the whole milk for initial distribution, against the inner periphery of said circular zone. 90

4. A centrifugal cream separator, comprising a bowl having an axial feed conduit, cream and skim-milk outlets, a plurality of separating members spaced apart, one within another, the lower portion of said members being circular in cross-section and the upper portion elliptical, the inner one of said members having openings in the upper portion for the passage of milk outwardly, while that by which it is inclosed is provided with openings in the lower portion for the outward passage of skim-milk. 100

5. A centrifugal cream separator, comprising a bowl having an axial feed conduit, cream and skim-milk outlets and spaced separating members between the axis and the inner periphery of the bowl, the base portion of said members being circular and the portion above said base elliptical in cross-section, said members being provided with openings for the passage of milk, one in the upper and the other in the lower portion, said upper openings being in the innermost member. 115

6. A centrifugal cream separator comprising a bowl having a whole-milk inlet, cream and skim-milk outlets and a separating member divided into horizontal zones of varying cross-sectional form, all parts of the 120

125

130

lowermost zone being substantially concentric with the axis, while areas of the other are disposed at different relative distances from said axis, and means for feeding the
5 whole-milk in thin films against the inner periphery of said circular zone.

In testimony whereof, I have signed this

specification in the presence of two subscribing witnesses, this 22d day of May, 1913.

JOHN P. HULTGREN
